(57) **CLAIM**

I claim the ornamental design for a nuclear medical imaging apparatus, as shown and described.

DESCRIPTION

FIG. 1 is a perspective view of a nuclear medical imaging apparatus according to the present invention;

FIG. 2 is a front elevational view of the apparatus of FIG. 1; FIG. 3 is a rear elevational view of the apparatus of FIGS. 1 and 2;

FIG. 4 is a side elevational view of the apparatus of FIGS. 1–3;

FIG. 5 is a bottom plan view of the apparatus of FIGS. 1–4; FIG. 6 is a side elevational view of the apparatus of FIGS. 1–5, showing the side opposite the side shown in FIG. 4; and,

FIG. 7 is a top plan view of the apparatus of FIGS. 1–6.
